UNITED STATES PATENT OFFICE.

JOSEPH D. FROMAN, OF VEVAY, INDIANA.

AMUSEMENT DEVICE.

1,422,688.

Specification of Letters Patent. Patented July 11, 1922.

Application filed December 8, 1920. Serial No. 429,130.

To all whom it may concern:

Be it known that I, JOSEPH D. FROMAN, a citizen of the United States, residing at Vevay, in the county of Switzerland and

5 State of Indiana, have invented certain new and useful Improvements in Amusement Devices; and I do hereby declare the following to be a full, clear, and exact description of the invention, such as will enable 10 others skilled in the art to which it appertains to make and use the same.

This invention relates to an amusement device, and the object is to provide mechanical means for imparting movement to a 15 figure or automaton suspended above a platform or dancing floor.

A further object is to provide for mounting the figure by means of an elastic device and an adjusting element, the former permitting 20 of movement in various directions, and return to normal position, and the latter providing for vertical adjustment.

A still further object is to provide a 25 figure comprising a body portion, with pivotally mounted arms and legs, and a head mounted for movement in various directions,—with means for imparting movement to the automaton thus constructed.

A still further object is to provide driving 30 mechanism comprising a motor, a crank shaft, and a pitman connected directly with means actuating the automaton, thus effecting direct and positive movement, the elastic element cooperating with the direct mechanical action in producing the desired 35 results.

With the foregoing and other objects in view, the invention consists in the novel construction, combination, and arrangement of 40 elements hereinafter described, it being understood that modifications or variations in construction may be made within the scope of the claims, without departing from the spirit of the invention.

45 Figure 1 is a perspective view of an amusement device constructed in accordance with my invention, some of the dancing figures or automata being omitted.

Figure 2 is a sectional view taken on the 50 plane indicated by the line 2—2 of Figure 1, looking in the direction indicated by the arrow.

Figure 3 is a sectional view taken on the 55 plane indicated by the line 3—3 of Figure 1, looking in the direction indicated by the arrow.

Figure 4 is a sectional view taken on the plane indicated by the line 4—4 of Figure 1, looking in the direction indicated by the arrow, and

60

Figure 5 is a detail view in side elevation of one of the dancing figures or automata, illustrating the construction thereof.

The automaton per se comprises a body portion 10, the head being designated 12 65 and being mounted on the shoulders 13, by means of the connection shown at 14, permitting of movement in various directions.

The arms each comprise a plurality of elements 15 and 16, these members being 70 pivotally connected at 17 to form a joint corresponding with the elbow. The legs each include an upper section 18 and a lower element 19, these members being pivotally connected at 20 to form a joint corresponding with the knee joint. The feet are shown at 21 and 22. The automaton thus constructed is shown in the drawing, and in a separate view, or in another portion of the drawing, I have shown a figure 80 of similar proportions provided with clothing and constituting the representation of a man in the act of dancing.

A platform 24 is of suitable proportions and connected with the rear portion thereof 85 of is a vertical wall 25 mounting an upper horizontal wall 26. The vertical supporting element, may, however, consist merely of a frame.

Extending across the element or wall 26 90 at a slot 26^a thereof is a transverse bar 27 and mounted in the latter are adjusting screws 28 each bearing on a resilient element, such as a steel spring arm 29, and the latter being connected with an elastic 95 cord 31, which depends through the slot 26^a and in turn is connected with the head of the figure, with the result that the upper portion of the device is movable in various directions, when direct mechanical movement is imparted to another portion of the figure.

An electric motor is shown conventionally at 32, the shaft thereof carrying a pulley 33 driving a belt 34 which passes around a pulley 35 mounted on crank shaft 36. A pitman 37 is connected with the crank shaft and has pivotal connection at 38 with the floor or platform 24, with the result that movement is imparted to the figures by 110 raising and lowering the floor incident to the rotation of the crank shaft. As the feet

of the automaton normally rest on the floor, the upward thrust imparted will tend to move the feet in such manner that the legs will bend at the knee joint. This action, together with the resilient suspending means produces the required result. It should be added that the platform is mounted on pivots, such as 40 and is supported in the main frame 41. Any suitable number of figures may be mounted in the manner specified.

What is claimed is:—

1. A toy consisting of an articulate figure, means to suspend said figure, an inherently rigid platform, means to pivotally mount said platform, and means to bodily rock said platform on its pivot for cooperation with the figure to impart simulative dancing movement thereto.
2. A toy consisting of an articulate figure, means cooperating with said figure to impart simulative dancing movement thereto, suspending means for the figure comprising an arm, and an adjustable member movable

against said arm to vary the elevation of 25 said figure.

3. A toy consisting of an articulate figure, a frame, a platform within the frame raised relative to the base thereof, means pivotally mounting said platform, a pitman depending from the platform, a shaft having a crank cooperating with said pitman, means to operate said shaft, a wall disposed over and at a distance from said platform, means mounting said wall on said frame, said wall 30 having a slot therethrough, a bar on said wall disposed over said slot, a spring arm secured to said bar, a screw adjustably threaded in the bar engageable with said arm, and means extending from said arm 35 through said slot to directly suspend said figure.

In testimony whereof I affix my signature in presence of two witnesses.

JOSEPH D. FROMAN.
